UNITED STATES PATENT OFFICE.

CARL AUGUST JOERISSEN, OF WASHINGTON, DISTRICT OF COLUMBIA, ASSIGNOR TO UNDERWOOD TYPEWRITER COMPANY, OF NEW YORK, N. Y.

TABULATOR.

SPECIFICATION forming part of Letters Patent No. 777,286, dated December 13, 1904.

Application filed March 22, 1904. Serial No. 199,463. (No model.)

To all whom it may concern:

Be it known that I, CARL AUGUST JOERISSEN, a citizen of the United States, and a resident of Washington, in the District of Columbia, have 5 invented certain new and useful Improvements in Tabulators for Type-Writing Machines, of which the following is a specification.

My invention relates to tabulators of that 10 class in which stops are mounted in position to be moved into and out of the path of a part of the paper-carriage, so that said stops may be set to arrest the carriage at certain points. The preferred embodiment of this class of 15 tabulators has the stops mounted upon a tabulating-frame which normally holds the stops out of position to engage the carriage, but which may be shifted into position to engage the carriage by means of the so-called "tabulator-key," and when so shifted or held into 20 engaging position the stops carried by said frame will successively arrest said carriage as the engaging projection reaches the successive stops. These arrangements have usually 25 been further provided with means whereby the pressing of the tabulator-key will release the escapement, so that the carriage remains directly under the influence of its feed-spring until arrested by the first stop to be encountered, the tabulator-key being released and 30 again pressed, if desired, as each stop comes into play to permit the carriage to move on to the next stop. In this class of tabulators it has been the custom to set the stops in different 35 positions corresponding to points at which it is desired to arrest the carriage in writing tabulating-work. It frequently happens that an operator desires to use a writing-machine for more than one form of tabulated 40 work, and in such cases it becomes a matter of inconvenience to frequently shift some or all of the stops to adapt the machine for the different forms.

The object of my invention is to overcome 45 the inconvenience referred to; and my invention consists in providing the tabulating portion of the type-writer with means whereby groups or series of stops may be set simul-

taneously by a movable member which controls their position. This movable member 50 is preferably in the form of a bar having longitudinal movement on or relatively to the tabulating-frame and having means for engaging the stops to move them or to determine their movements into and out of effective position 55 on the tabulator-frame. These engaging means on the controller-bar are so located or are so constructed that they may be located at will in such positions that on imparting one movement to the bar all of the stops desired 60 for use in one particular form of tabular work will be moved into effective position, while all of the remaining stops move into ineffective position, and thereafter on imparting another 65 movement to the bar another grouping of the stops of the tabulator will be set for doing tabular work on another form. The engaging means on the controller-bar may be so located that some of the stops will remain in effective position in all groupings of the stops— 70 as, for instance, when such stops are common to all of the forms for which the machine is to be set. I shall illustrate my invention by means of a controller-bar which engages the stops to move them out of effective position 75 and permits the stops to move into effective position under the action of a spring or similar means combined with each stop; but obviously these conditions might be reversed, so that the stop is moved into effective position by engagement of the controller-bar and provided with means which causes it to assume ineffective position when disengaged by the controller-bar, or the controller-bar might be arranged to positively move the stops in both 80 directions. Again, I have employed for purposes of illustration a controller-bar which causes but two groupings of the stops by its movements in opposite directions; but obviously this bar could be made to assume a number of positions intermediate of its two opposite limits of movement, each of which positions would cause a separate grouping of the stops, and this without departing from the spirit of my invention. 85

In order that the invention may be more 95

fully understood, I will now proceed to describe the same with reference to the accompanying drawings, which show one embodiment of the invention by way of illustration.

5 In said drawings, Figure 1 is a rear view of the upper portion of a type-writer equipped with a tabulator of well-known construction and having my present improvement applied thereto. Figs. 2, 3, and 4 are plan views of the 10 tabulator-frame, showing the scale-bar, the relation to the stops thereto, and the sliding controller-bar with its cams for engaging the stops to move them out of effective position and to permit them to return to effective position when released, Fig. 1 showing the controller-bar disengaged from all the stops and Figs. 2 and 3 showing the controller-bar engaged with different stops to produce two 15 separate groupings of stops. Figs. 5 and 6 are a plan and an edge view of the controller-bar. Fig. 7 is a detail view of one end of the controller-bar, in which the cams or engaging means are shiftable or adjustable on said bar, so as to vary its scope of usefulness and 20 adapt it for any desired form of tabular work. Fig. 8 is a vertical sectional view of a portion of the tabulating-frame, showing a stop mounted thereon, the scale-bar for indicating its position, and the controller-bar by which the 25 stops are moved.

1 represents the tabulator-frame of a typewriter, having a bar 2, stops 3, mounted on said bar, and a scale 4, indicating the relative positions of the stops. The tabulator-frame is 30 constructed with teeth 5, which receive tongues 6, Fig. 8, on the stops to fix said stops in positions to which they may be adjusted. In order to shift the stops, they may be swung outwardly on the rod 2 until their tongues 6 35 disengage from the teeth 5, after which the stops may be slid longitudinally on the rod 2 to any desired position and thereafter swung inwardly again to bring their tongues in engagement with the teeth to hold the stops in 40 position. To hold the stops against swinging on the rod 2, spring-pressed balls 7 are fitted in pockets in the stops and made to engage in the longitudinal groove 8 in the rod 2. These balls, however, yield when the stops are swung outwardly—as, for instance, by downward pressure on the knob 9—and to hold them in their outer position until they are properly adjusted 45 bar 2 is provided with an additional groove 10, which receives the balls when the stops are in their outward position. Each stop is provided 50 with a projection 11, through which it engages the carriage when the tabulator-frame is swung inwardly toward the carriage. When a stop is swung outwardly on the frame, projection 11 does not enter the path of the carriage, and such a stop is therefore inoperative or is ineffective or is in ineffective position.

As thus far described the parts are known in the prior art of tabulators for writing-ma- 55 chines. In carrying out my present invention

according to the embodiment adopted for illustration I provide means for moving the stop 3 outwardly in opposition to its retaining-ball 7, so as to render such stop ineffective and for disengaging the stop, so as to permit it to return to normal position when it is desired that the stop shall be effective, this outward movement of the stop, however, not being sufficient to permit the ball 7 to pass into the outer groove 10, so that said ball will tend to return 70 the stop and not hold it in its outer position. To impart movement to the stops, I employ a controller-bar 12, which is conveniently mounted beneath scale 4 and secured in position by the screws 13, which hold said scale, the controller-bar being held by longitudinal slots 14, so that it may move longitudinally beneath the scale. The controller-bar 12 carries cams 15, which when the bar is moved longitudinally will engage the index-fingers 80 16 on the stops and impart a sufficient movement to said stops to carry their engaging projections 11 out of effective position. The cams 15 are so located that when the bar is moved to one limit of its motion one group of stops 90 will be engaged and moved out of effective position, while the remaining stops form a grouping in effective position to arrest the carriage successively at different points corresponding to a ruled form to be written on. 95 When the controller-bar is moved to the other limit of its motion, the engaged stops will be released and permitted to return to effective position, while the remaining stops or some of them will be moved out of effective position and a new grouping of stops corresponding to a different form to be written will have 100 been established. It may happen that some stops are common to both forms for which the machine is adjusted, in which event the 105 displacing-cam on the controller-bar corresponding to such a stop will be omitted and such stop will be in effective position at all times. As shown in Fig. 2, the controller-bar 110 may be stopped at an intermediate position, in which none of the stops will be engaged and all will remain effective, thus giving a third grouping of the stops. Obviously this third grouping could be modified so that some of the stops could be thrown out. In 115 fact, the invention is susceptible of a wide range of application in forming different groupings of stops, the range of longitudinal movement of the controller-bar being correspondingly provided for. The controller-bar 120 12 may have the cams formed integral with it, as shown in Fig. 5, in which case a special bar would be made for any particular set of forms for which it is desired to adapt the machine. The controller-bar being extremely 125 simple and cheap in construction and being easily replaced could readily be made for any special purpose, or the controller-bar may be constructed as suggested in Fig. 7, in which each cam 15^a is inserted in the seat 15^b, formed 130

in the controller-bar and there secured by a screw 15°. This arrangement provides for setting the cams in such positions as to obtain any desired groupings of the stops, range of 5 which is very wide in view of the longitudinal adjustability of the stops themselves on the rod 2.

Having thus described my invention, the following is what I claim as new therein and 10 desire to secure by Letters Patent:

1. In a tabulator, the combination of a frame or support, a stop thereon movable into and out of effective position and a controller-bar sliding parallel to the frame or support 15 and controlling the position of the stop.

2. In a tabulator for type-writers, in combination with the paper-carriage and tabulator-frame; stops carried by one of said parts and movable into and out of effective position, 20 means for bringing the stops on one of said parts into engagement with the other of said parts to arrest the paper-carriage, and means sliding parallel to the part which supports the stops, adapted to engage the stops and move 25 them into and out of effective position.

3. In a tabulator for type-writers, the combination of a series of stops having means for yieldingly holding them in effective position and a longitudinally-movable bar engaging 30 said stops to move them out of such position.

4. In a tabulator for type-writers, the combination of the tabulator-frame, stops carried thereby and independently movable thereon to and from effective position, and a control-

ler-bar mounted on said tabulator-frame controlling the positions of said stops. 35

5. In a tabulator for type-writers, the combination of a tabulator-frame, stops carried thereby and independently movable thereon to and from effective position, a controller-bar reciprocating on said tabulator-frame and cams carried by said controller-bar adapted to engage the stops for controlling their positions. 40

6. In a tabulator for type-writers, the combination of a tabulator-frame, stops carried thereby and independently movable into and out of effective position thereon, a controller-bar mounted to reciprocate on said frame, and cams carried by said controller-bar engaging 50 the stops to control their positions; said cams being positioned on the bar to engage some of the stops when the bar is in one position and to engage others of the stops when the bar is in another position. 55

7. In a tabulator for type-writers, the combination of the stops, the controller-bar reciprocating relatively to the stops, and the cams on the controller-bar engaging the stops to control their positions; said cams being 60 adjustable for the purpose set forth.

The foregoing specification signed this 9th day of March, 1904.

CARL AUGUST JOERISSEN
